ATTACHMENT TO WRINGER

Filed Dec. 27, 1929

FIG. 1

FIG. 2

FIG. 3

Inventor
J. W. Stainsby

AS

J. W. Stainsby

UNITED STATES PATENT OFFICE

JOHN W. STAINSBY, OF WINNIPEG, MANITOBA, CANADA

ATTACHMENT TO WRINGER

Application filed December 27, 1929. Serial No. 416,938.

- The invention relates to improvements in attachments to wringers and particularly to wringers for clothes washing machines and an object of the invention is to provide an attachment which will feed the clothes to and between the wringer rollers and thereby prevent any possibility of one getting his fingers caught between the rollers as occurs at the present time where no such device is used.
- 5 A still further object of the invention is to provide an attachment which can be installed on the existing type of wringers without requiring any alteration in the structure thereof and to design the attachment in a simple, durable and inexpensive manner.
- 10 With the above more important objects in view, the invention consists essentially in the arrangement and construction of parts hereinafter more particularly described, reference being had to the accompanying drawing, in which:—
- Fig. 1 is a perspective view of a wringer provided with my invention.
- 15 Fig. 2 is a vertical sectional view centrally through the wringer.
- Fig. 3 is a perspective view of one of the supporting brackets utilized.
- 20 Fig. 4 is a vertical sectional view longitudinally through one of the belt carrying rollers which I provide.
- Fig. 5 is a perspective view of a modified type of bracket.
- 25 Fig. 6 is an enlarged detailed horizontal sectional view at 6—6 Figure 2, the wringer roller and the bearing being shown in plan view.
- In the drawing like characters of reference indicate corresponding parts in the several figures.
- 30 40 I have herein shown and described my invention as associated with a well known type of power driven wringer and as is well known, the clothes, after having been washed, are fed to the wringer between the upper and lower rollers thereof. There are appliances now used for releasing the fingers should they get caught between the wringer rollers but according to my invention, it is not necessary for the operator to place his hands near the rollers in feeding the wringer as the clothes are carried to the rollers by endless belts provided.
- 35 The upstanding stationary standards or sides 1 and 2 of the wringer are provided on their inner faces each with a vertically disposed channel or slideway 3 and in the type of wringer shown, the channel is provided with vertical guide ribs 3' between the inner edges of which a vertical slot 3" is reserved.
- 40 The lower ends of the channels are closed by an inturned horizontal stop web 3" (see Figure 2). The bearing blocks or ball bearing casings 4 which are utilized to support rotatably the wringer rollers are slidably entered in the rear parts of the slideways between the vertical ribs 3' and the back walls of the channels as best shown in Figure 6. The lower bearing casings rest on the webs 3".
- 45 The wringer rollers 5 and 6 have the spindles 7 thereof passing through the slots 3" and 70 rotatably carried by the ball bearings. The upper roller is always pressed towards the lower roller and various means are provided so that the adjustment can be varied. I have herein shown adjustable pressure springs 9 but as this arrangement forms no part of my invention, it is not herein further described.
- 50 75 When a wringer of the type disclosed is to be equipped with my invention, it is provided with a pair of brackets 10, one of which is shown in Figure 3. It will be observed that the bracket has a channel shaped body part 11 and that the body part carries a pair of outstanding horizontally disposed arms 12 and 13 of predetermined length. It will also be noticed that the back wall of the body part is vertically slotted at 14 and 15. The brackets are inserted one at each end of the wringer with the channel shaped body parts 11 entering the channels 3 of the standards and the back wall of the body part in each instance is positioned between the ends of the rollers and the vertical ribs 3' and the shafts 7 pass through the slots 14 and 15.
- 80 90 The under side of the body part of each bracket rests on the inturned web 3" which closes the lower end of the channel and the shoulders 11' of the body part engage with the side walls of the channel. Accordingly when the brackets are inserted, they are held
- 95 100

up by the webs 3², are prevented from rotating in the vertical plane by contact of the shoulders 11' with the side walls of the channels and the slots 14 and 15 permit of the free 5 passage of the roller shafts.

Each of the arms 12 and 13 is provided with end holes 16 and 17 which receive the ends of similar parallel cross shafts 18 and the shafts are fastened permanently to the 10 ends of the arms by inner and outer nuts 19 and 20 thereon. By adjusting the nuts on the ends of the shafts, I can spread the brackets so that the outer faces thereof are pressed tightly into contact with the standards at the 15 points indicated by the reference characters A Figure 6 and this also insures of the effective holding of the brackets in place.

On each shaft, I mount a roller 21 which is hollowed out to receive the shaft and which 20 has tubular bushings 22 and 23 inserted in the ends thereof and rotatably mounted on the shaft. The rollers employed are shown as provided with equi-spaced peripheral channels 24 and the surface of the roller between the 25 channels is shaped to provide arched wheel-like rims 25. Similar endless belts 26 are passed around the wheel-like rims of the rollers as best shown in Figure 1, there being a space reserved at 27 between the successive 30 belts. The belts are substantially horizontal and they have the upper sides thereof passing between the wringer rollers.

When this device is in use, the driven 35 wringer roller drives the belts in the direction of the applied arrow Figure 1 and the clothes, which have been previously washed, are placed on those parts of the belts moving towards the rollers 5 and 6 so that the clothes are fed to the wringer without necessitating 40 placing the fingers of the hand in the area near the wringing rollers. By providing a number of belts with spaces therebetween the water liberated from the clothes is free to flow down back into the wash tub (not 45 shown) and by arching the rims as at 25, I insure that the belts remain in place on the rollers.

It will be obvious that this device can be very easily and quickly placed on existing 50 wringers as far as I am aware, they are all provided with vertical slides for receiving the wringer roller bearings and it is accordingly an easy matter to put the brackets in place and once in place they are held against 55 escaping as will be readily understood.

I might remark also that there are certain types of washing machines made which have hinged lids for the tubs, the lids being thrown upwardly towards the wringer when opened. 60 Where such a tub is encountered, it is desirable to make one of the arms of each bracket jointed so that it can be swung upwardly to permit of the up swinging of the lid. A bracket of this nature is shown in Figure 5 65 where it will be observed that the arm 12 of

the bracket is shortened and carries a hooked or L-shaped lug 28 and that an extension arm 29 is pivotally connected by a pivot bolt 30 to the short arm 12.

The extension arm has the free end thereof provided with a hole 31 similar to that 17 for receiving the end of the shaft 18 and I might here remark that the arm 29 has the outer end thereof slightly lower than the inner pivoted end when it is resting on the catch, this insuring that it will remain in its down position when the belts are operating, the tension in the belts holding the extension arms down.

What I claim as my invention is:—

1. In a wringer, the combination with end standards providing vertical slideways, bearing blocks contained in the slideways and upper and lower wringer rollers having the spindles thereof rotatably carried by the blocks, of similar horizontally disposed brackets having portions thereof shaped to enter the slideways and slotted to receive the roller spindles, rollers located between and carried by the ends of the brackets and endless belts carried by the latter rollers and having the upper portions thereof passing between the wringer rollers.

2. In a wringer, the combination with end standards providing vertical slideways, bearing blocks contained in the slideways and upper and lower wringer rollers having the spindles thereof rotatably carried by the blocks, of a pair of horizontally disposed opposing brackets located to the inner sides of the standards and having the central portions thereof shaped to enter the channels and engage the side walls thereof and vertically slotted to receive the ends of the roller shafts, tie rods connecting the extending ends of the bracket, rollers mounted on the tie rods between the brackets and endless belts carried by the latter rollers and having the upper sides thereof passing between the wringer rollers and the under sides thereof passing under the lower wringer roller.

3. In a wringer, the combination with end standards providing vertical slideways, bearing blocks contained in the slideways and upper and lower wringer rollers having the spindles thereof rotatably carried by the blocks, of a pair of opposing horizontally disposed brackets located to the inner sides of the standards and having the central portions thereof shaped to enter the channels and contact with the side walls thereof and to receive the ends of the rollers and vertically slotted to receive the roller spindles, tie rods permanently connecting the extending ends of the brackets and spacing them apart and endless belts carried by the latter rollers and having the upper sides thereof passing between the wringer rollers and the under sides thereof passing under the lower wringer roller.

sides thereof passing underneath the lower wringer roller.

4. In a wringer, the combination with end standards providing vertical slideways, bearing blocks contained in the slideways and upper and lower wringer rollers having the spindles thereof rotatably carried by the blocks, of a pair of opposing horizontally disposed brackets positioned at the inner 10 sides of the standards and provided centrally of their length with channel shaped portions entering the channels aforesaid and contacting with the side walls thereof, the back walls of such channel shaped portions 15 being located at the ends of the rollers and vertically slotted to receive the roller shafts, tie rods permanently connecting the extending ends of the brackets together, rollers mounted on the tie rods and endless belts 20 carried by the latter rollers and having their upper sides passing between the wringer rollers and their under sides underlying the lower wringer roller.

5. A supporting bracket presenting an 25 elongated body having an intermediate part channel shaped in horizontal cross section, the back wall of said channel part being vertically slotted at its upper and lower edges and the extending ends of the elongated body 30 being provided with shaft receiving openings.
